(57) **CLAIM**

The ornamental design for a merchandiser facade, as shown and described.

DESCRIPTION

FIG. 1 is a perspective view of a merchandiser façade of our new design;

FIG. 2 is a front elevation view thereof;

FIG. 3 is a right side elevation view thereof;

FIG. 4 is a top plan view thereof; and,

FIG. 5 is a left side elevation view thereof.

Features forming no part of the claimed design are illustrated in broken lines.

1 Claim, 5 Drawing Sheets(56)
